DESIGN FOR A GAME BOARD

Gerard L. Van der Hoeven, Taylorsville, Calif.

Application April 8, 1936, Serial No. 62,017

Term of patent 14 years

To all whom it may concern:

Be it known that I, Gerard L. Van der Hoeven, a subject of the Queen of Holland, residing at Taylorsville, in the county of Plumas and State of California, have invented a new, original, and ornamental Design for a Game Board, of which the following is a specification, reference being had to the accompanying drawing forming a part thereof.

The figure is a perspective view of the game board showing my new design. The printed matter and numerals appearing on the figure are merely illustrative.

I claim:—

The ornamental design for a game board as shown and described.

G. L. VAN DER HOEVEN.
